REVERSIBLE CASEMENT FRAME

Filed Sept. 13, 1929

UNITED STATES PATENT OFFICE

GEORGE M. KLEINKNECHT, OF FORT LEE, NEW JERSEY

REVERSIBLE CASEMENT FRAME

Application filed September 18, 1929. Serial No. 392,335.

The present invention has reference to a reversible casement frame of stock size which is so constructed that the same size sash or storm sash and also the same size screen can 5 be made to swing either in or out of the frame by merely shifting the stops and sub-sills of the frame.

A further object is the provision of a casement sash frame of standard heights and 10 same height sashes for swinging in or out of the frame as well as one same size screen for also swinging either inwardly or outwardly so that such frames and sashes can be carried in stock by the dealer to accommodate the 15 trade and eliminating the necessity and expense and trouble of constructing two different types of frames to accommodate either outward or inward swing sashes.

Other objects of the invention will appear 20 from the following detailed description which is to be read in connection with the accompanying drawings.

In the drawings:

Figure 1 is a vertical transverse sectional 25 view through the improvement, the screen frame being arranged upon the outer face of the frame and the sash upon the inner face thereof.

Figure 2 is a similar sectional view but 30 showing the stop and auxiliary sill adjusted to permit of the sash being arranged upon the outer face of the frame and the screen upon the inner face thereof.

Figure 3 is a horizontal sectional view approximately on the line 3—3 of Figure 1.

Figure 4 is a similar sectional view on the line 4—4 of Figure 2.

Referring now to the drawings in detail, and to Figures 1 to 4 in particular, the sill 40 of the casement frame is indicated by the numeral 8. The sill, on its inner edge is provided with the usual transverse groove for the reception of the tongue of the stool of the frame. The side and head jambs of the frame 45 which are of the same pattern are indicated by the numeral 9 and the outer casing of the side and head casing by numeral 11.

The top and side casing is provided with a groove to receive a fillet which fillet is on 50 the side and head jambs at approximately

the center thereof. In the groove 10, in the sill 8, there is received the tongue 12 of the auxiliary or sub-sill 13, while in the grooves 16 of the side and head jambs there is received the tongue 14 of the vertical and head 55 stop strips 17. The stop strips 17 and the auxiliary sill 13 are of the same width. Tongues 12 of the auxiliary sill 13 and the tongues 14 of the stops 17 are of the same width and the groove 10 in the sill 8 and 60 groove 16 of the side and head jambs are larger in width than the tongues 12 and 14 by a difference between the thickness of the sash and screen:

Example:—If the sash is $1\frac{3}{8}$ " and the 65 screen $1\frac{1}{16}$ " this open space in grooves 10 and 16 will be $\frac{5}{16}$ of an inch.

In this manner it will be noted that the 70 stop strips and auxiliary sill may be shifted or moved laterally in the frame, as disclosed by Figures 1 and 3 of the drawings which will permit of the sash 18 being shifted in the inner face of the frame for in-swinging and the storm sash or screen frame 19, may be shifted in the outer section. By moving 75 the stop strips and the auxiliary sill to the position disclosed by Figure 2 of the drawings, it will be noted that the sash 18 and the screen frame 19 may be reversely arranged.

A window which is large in width may be 80 divided by one or more mullion rails 12, which has its opposite faces provided with grooves 21 that register with the grooves 16 which are of the same width and depth as the said groove. In these instances, of 85 course, extra auxiliary sills and extra inner stop strips 17 are provided.

The said strips being formed on their inner or confronting faces with the tongues 22 that are to receive in the said grooves 21 90 which said grooves are the same as 16 in the side of head jambs.

As disclosed by the drawings the outer 95 face of the auxiliary sill 13 is beveled and has its inner edge enlarged to form the same with a bead 23, and this bead is covered by a water drip strip 24 that is secured to the outer face of sash frame when sash swings in.

It is obvious that sash of greater thicknesses can be used in this frame. If thicker 100

sash swing out, the outer edge of stops 17 and auxiliary sill 18 can be dressed down to accommodate this thicker size. If thicker sash swings in, inner edge of stops 17 can be dressed down and auxiliary sill 18 remaining the same, bottom rail of sash can be rabbeted over bead 23 omitting drip 24.

It will be noted that the sash height, screen height, storm sash height, all remain the same for either swinging in or swinging out.

Having described the invention, I claim:

A reversible casement frame comprising a main sill having a groove, top and side jambs associated with the sill and having grooves therein of equal width with the width of the first named groove, an auxiliary sill located on the main sill, a tongue on the auxiliary sill and extending into the first mentioned groove and of a width less than the width of the first mentioned groove, stop strips associated with the top and side jambs, tongues on said strips and of corresponding width with the width of the first mentioned tongues and extending into the second mentioned grooves, and sashes of different thicknesses abutting the strips and auxiliary sill and by shifting the strips and auxiliary sill laterally the sashes may be reversed relative to each other.

In testimony whereof I affix my signature.

GEORGE M. KLEINKNECHT.
